UNITED STATES PATENT OFFICE.

FRANK S. SMALL, OF NEW YORK, N. Y.

BRIDGE-ABUTMENT CONSTRUCTION.

1,306,725.

Specification of Letters Patent. Patented June 17, 1919.

Application filed May 9, 1918. Serial No. 233,491.

To all whom it may concern:

Be it known that I, FRANK S. SMALL, a subject of the King of Great Britain, residing at New York, in the county of New 5 York and State of New York, have invented certain new and useful Improvements in Bridge-Abutment Construction, of which the following is a specification.

This invention relates to improvements in 10 abutments for bridges and like structures erected in rivers and similar localities, and has for one of its objects to cheapen the construction where satisfactory foundation material is at so great a depth as to render 15 it unduly expensive to carry the masonry or concrete down to such foundation material.

With these and other objects in view, the invention consists in certain novel features of construction, as hereinafter shown and 20 described and then specifically pointed out in the claims; and in the drawings illustrative of the preferred embodiment of the invention—

Figure 1 is a side elevation, partly in section, illustrating the improved construction, 25

Fig. 2 is a plan view of the parts shown in Fig. 1 without the concrete structure of one of the abutments,

Fig. 3 is a section on the line 3—3 of 30 Fig. 1.

The improved apparatus comprises two oppositely disposed abutments to support the ends of a bridge or like structure each with a foundation of crossed timbers or 35 cribs suitably united with each other and the weight of the abutment carried on piles driven through the crib. The foundation cribs are connected by a system of timbers which couple the foundations, preferably 40 near their lower sides, and extend transversely of the stream over which the bridge is to be constructed and sufficiently below the surface of the water to avoid interference with navigation and the discharge of 45 the stream. The connecting timbers form a strut and operate to resist the pressure or horizontal thrust and obviates the necessity for carrying the abutments down to bed rock. The concrete superstructure is erected 50 upon the foundation timber-work of each abutment. The foundation members are precisely alike and the description of one will suffice for both. The foundation structure is formed of a plurality of timbers 10 in 55 spaced relation both vertically and horizontally and supported transversely of the

stream or other body of water over which the bridge is to be constructed, and a plurality of timbers 11 likewise disposed in spaced relation both vertically and horizontally and extending longitudinally of the line of the stream or other body. The timbers 10 and 11 thus cross each other at right angles in "cob-like" relation as shown, the timbers 10 and 11 where they cross each other 60 being slightly dovetailed as illustrated. A plurality of anchoring piles represented at 12 are driven through the openings between the timbers and into the ground beneath them. The crossed and anchored timbers 65 are shown arranged with an open space indicated at 13 at the land or shore side but the device may be applied to any form of abutment construction. When a U-shaped abutment is employed, one or more of the 70 timbers 11 may be extended across the open space as shown in Fig. 2, if deemed desirable. The upper series of the timbers 11 are covered by a floor represented at 14 to receive the concrete superstructure indicated 75

at 15. The upper ends of the piles 12 extend above the line of the floor 14, and the upwardly projecting portions are embedded in the concrete as shown in Fig. 1. Prior to the placing of the concrete in position 80 a plurality of wedges illustrated at 16, will be forced between the floor 14 and each of the piles 12 to force the piles over as far as possible toward the waterway and thus prevent horizontal motion of the masonry 85 when the earth or other back filling is placed. The timber work if necessary, will be further strengthened and reinforced by diagonal braces, one of which is indicated at 17. At their lower portions the timber 90 work foundation structure is united by a reinforcing and coupling structure composed of a plurality of timbers 18 disposed in a plurality of horizontal rows in spaced relation, the rows being maintained in separated 95 position by transverse tie timbers 19. At their terminals the timbers 18 extend between the transverse members 11 of the abutment foundation and form continuations of the crib members. By this means 100 the foundation crib-work of the opposite abutments are firmly coupled and united and supported from displacement or movement toward each other. The coupling structure extending between the two cribs operates 110 as a strut to take the horizontal pressure of the filling behind the abutments. The

amount and position of the bracing required in the coupled structure will vary according to circumstances. The coupling members 18 and 19 are maintained at a sufficient distance below the water line to prevent interference with the navigation of the stream, and likewise to insure constant immersion to avoid decay.

In building bridge abutments heretofore 10 in "soft" localities, the excavations are extended to safe material and this is generally an expensive operation. By employing the improved construction, it is necessary to excavate only to a depth necessary for the timber cribs, the piles being driven to the bottom of the excavation to safe foundation.

The work can be done much quicker, danger of interruption by floods is lessened, the amount of excavation reduced, and the 20 concrete required in many cases will be but a fraction of that called for if it were carried down to firm foundation material. Long and expensive fills are often made across coves or small bays, marshes, and 25 swamps, because it is cheaper to make the fill than to carry the road on piers owing to the bad foundation material. Also these fills may seriously obstruct the water way during flood stages. By the use of the invention 30 here described it will in many cases be cheaper to use piers resting on a crib and pile foundation than to fill the depressed localities.

Having thus described the invention, what 35 is claimed as new is:

1. A structure of the class described including spaced cribs formed of interlocking longitudinal and transverse timbers, tie members connecting the lower portions of 40 the cribs below the water line of the structure and interlocked with the transverse timbers thereof, piles extending vertically through the cribs, and means engaging the piles for bracing them against the transverse 45 timbers of the cribs.

2. A structure of the class described including spaced cribs formed of interlocking longitudinal and transverse timbers, tie members of less height than the cribs connecting the lower portions of the latter below the water line of the structure and interlocked with the transverse timbers of said cribs, a floor for each crib, piles extending through the cribs and projecting above the

adjacent floor, and wedge devices bearing 55 against the piles at said floor for forcing said piles in engagement with the transverse timbers of the cribs.

3. A structure of the class described including spaced cribs formed of interengaging longitudinal and transverse timbers, tie members connecting the cribs below the water line of the structure and of less height than said cribs, a floor for each crib provided with openings having slots communicating therewith, piles extending through the openings in the floors and bearing against adjacent transverse timbers of the cribs with their upper ends projecting above the floor line, and wedges inserted in the 60 slots and bearing against the piles.

4. A structure of the class described including spaced cribs formed of interengaging longitudinal and transverse timbers, longitudinal superposed tie members connecting the cribs below the water line of the structure and of a combined height less than the height of said cribs, a floor forming a 75 top for each crib, piles bearing against the transverse timbers of the cribs and having 80 their upper ends extended through and projecting above the floors, and a superstructure formed of cement resting on the floor of each crib and covering the projecting ends of the piles.

5. A structure of the class described including spaced cribs formed of interengaging longitudinal and transverse timbers extending the entire height and width of the cribs, tie members connecting the lower 90 portions of the cribs and extending therethrough and interlocked with the transverse timbers of the cribs, a floor for each crib, there being slots formed in the floor, piles extending through the floor and bearing against adjacent transverse timbers of the cribs, the upper ends of said piles being extended above the floor line of the cribs, wedges insertible in the slots above the floor 95 line and bearing against the piles for forcing the piles into engagement with the adjacent transverse timbers of the cribs, and a concrete superstructure mounted on the floor of each crib and covering the projecting ends of the piles and said wedges.

In testimony whereof I affix my signature.

FRANK S. SMALL [L. S.]
